UNITED STATES PATENT OFFICE.

FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

LASTING-MACHINE.

1,323,714.

Specification of Letters Patent.

Patented Dec. 2, 1919.

Application filed April 21, 1916. Serial No. 92,577.

To all whom it may concern:

Be it known that I, FRANK W. MERRICK, a citizen of the United States, residing at Boston, in the county of Suffolk, State of Massachusetts, have invented a certain new and useful Improvement in Lasting-Machines, of which the following is a specification, reference being had therein to the accompanying drawings.

- 10 The invention has relation to lasting machines, and in particular to lasting machines of the type in which the upper of a shoe is drawn properly into place upon and around a last to which the same has been applied, by or through relative movement of the last with upper thereon and co-acting lasting devices, as for instance by or through entry of the last and upper within a nest or circle of lasting devices.
- 20 The invention comprises novel and improved means adapted to be employed for the actuation of the usual presser or hold-down of a lasting machine, but designed more especially for actuating a combined de-
- 25 pressor and hold-down for causing the relative approach and entry aforesaid and there-through bringing about the lasting operations by which the upper is drawn or wiped and stretched so as to conform to the shape
- 30 of the last and fit tightly and smoothly thereto. More particularly, the invention consists in fluid-pressure means for occasioning at the will of the operator, and under the continuous control of the latter, the relative approach, entry, and resulting lasting operations aforesaid.

One general object of the invention is to provide means for the said purposes capable of acting with a wide range of energy, and adapted to apply the operating force with intensity graduated at the will of the operator.

The drawings represent illustrative embodiments of the invention in connection with lasting mechanism on the order of that shown and described in U. S. Letters Patent No. 1,245,117, granted October 30, 1917, upon my application for U. S. Letters Patent filed April 28, 1913, Serial No. 50 764,005. Two of the said embodiments are represented, one thereof comprising a double-acting-cylinder arrangement and the other thereof a single-acting-cylinder arrangement.

In the drawings,—

Figure 1 shows in elevation certain portions of the lasting machine of my patent aforesaid with the double-acting-cylinder arrangement applied thereto.

Fig. 1^a is a view showing the controlling treadle.

Fig. 2 is a view similar to Fig. 1, showing the single-acting-cylinder arrangement applied.

Figs. 3 to 6 show details.

The lasting machine of the patent aforesaid, (partly shown herein) is a bed-lasting machine. It is characterized by containing means for causing the coming together or relative approach of the lasting devices and a last having an upper of a shoe applied thereto, and entry of said last and upper within said devices, and by containing also lasting devices that are actuated to draw the upper into place around the last by the said coming together or relative approach and resulting entry.

Herein, lasting devices on the order of those of the said patent are shown, they being collectively marked A. As the nature of the lasting devices has been indicated sufficiently, and is clearly disclosed in the patent aforesaid, specific description of the same is unnecessary.

In the machine shown and described in the said patent the means for causing the relative approach and entry comprises, essentially, a depressor and hold-down corresponding with that which is shown at 103 in the drawings forming a part of this specification, and mechanism for giving to the same at the will of and under the control of the operator movement to depress the last and shoe within the nest or circle of the lasting devices. Certain parts of the said mechanism as shown in the said patent are shown herein as utilized in the illustrative embodiments of the present invention. Thus, in the drawings, the said depressor and hold-down is supported by being connected with the lower end of an upright plunger-rod 104, and the movement aforesaid is provided for by mounting the plunger-rod in fixed guides 105, 106, in connection with the upper portion of the machine framework. The upper portion of the said plunger-rod, in addition to working in the fixed guide 106 enters also an upward extension 107 of said guide.

105

This portion of the plunger-rod is of reduced diameter, as shown, in order to provide at the upper end of the portion that works in guide 105 a shoulder 1041 against which is placed a collar 108 that is fixed upon the said reduced upper portion of the plunger-rod. The actuating devices for the plunger-rod and the depressor and hold-down are engaged with this collar. The 10 said actuating devices include a duplicated toggle-arrangement having the lower ends of the lower links or members 110 thereof connected to the opposite sides of the collar by pivots 109. The upper ends of the said links or members 110 are connected by pivots 111 to the lower ends of upper toggle-links or members 112, the upper ends of which in turn are connected by pivots 113 to the upper end of the fixed extension 107 of the 20 guide 106 for the plunger-rod. The duplication of the toggle-arrangement at opposite sides of rod 104 is in order to secure a balanced application of power to the said rod. Only the parts at one side of the rod are 25 shown in the present drawings. In the machine of the patent of October 30, 1917, to provide for the bending or straightening of the toggles as required for operating the plunger-rod and depressor and hold-down, 30 the intermediate pivots 111 of the toggles are connected by links 114 to opposite sides of a nut mounted upon a screw having means for turning the same by power in either direction when required, at the will of the operator. In the illustrative embodiments of 35 the present invention the invention is carried into effect by connecting the links 114 to pivots 115 at opposite sides of a piston a or a' working in a cylinder b or b' . The 40 said cylinder is suitably supported upon the upper part of the machine-frame.

The piston a or a' and cylinder b or b' pertain to the fluid-pressure-means aforesaid. Suitable provision is made in practice for supplying to the cylinder under the desired pressure the pressure-medium that is employed, and for controlling the action of such medium upon the piston. In the case of the double-acting-cylinder arrangement of Figs. 1, 3, and 4, the fluid-supply pipe x , Figs. 3 and 4, is connected by branches x' , x' , to the valve-casings c , c , at the opposite ends of the cylinder, each of the said valve-casings communicating by 50 suitable inlet and outlet ports with the interior of the cylinder b . The rotary valve-members d , d , within the said valve-casings are connected together by means of a link e so that such valve-members turn in unison, 55 and the turning of the said valve-members by the operator is provided for by means of a rod 126 which in practice is connected with a treadle 127, Fig. 1^a, pivoted at 128, and conveniently located for the use of the op-

erator, or if desired the said rod may be 65 connected with a suitable hand-lever.

The single-acting-cylinder arrangement of Figs. 2, 5, and 6, has a single valve c' at one end of the cylinder b' , with which valve the supply-pipe x^2 is connected, the rotary valve-member d' of the said valve being operatively connected with the controlling rod 126.

In Figs. 1, 3 and 4, the fluid-pressure is utilized to depress the depressor and hold-down and to hold it down, and also to raise the same. In Figs. 2, 5 and 6, the fluid-pressure is employed for the purpose of depressing and holding down the depressor and hold-down, the raising of the latter being effected by means of contracting spiral springs g' , (one at each side of the cylinder,) each connected at one end thereof with the connecting pivot 111 of the corresponding toggle-links 110, 112, and at the other 85 end connected to a pin h' projecting from the cylinder b' .

From what has been stated already herein, the principles of the invention, the purposes thereof, and the results that are secured thereby, will be clearly apparent.

Preferably an elastic pressure-medium, which may be air, steam or gas, is employed. The utilization and control of the elasticity of the said medium are important factors 95 of the invention.

The invention enables the depressor or hold-down to be actuated downward from its normal upwardly-retracted position, and depressed at any required speed and with any required energy, but with resilient action, upon an insole that has been mounted upon the bottom of a last. When a resilient pressure-transmitting medium is employed, the resiliency secures the advantage that when the depressor and hold-down lands against the insole the resistance may operate to retard or arrest the movement of the depressor and hold-down, last, etc., without injury to the upper. In case of such retardation or 110 arrest although the pressure behind the piston will gradually increase as the cylinder fills, sufficient time will be afforded the operator for either shutting off further inflow of the pressure-medium or else making any 115 required adjustments in connection with the upper, last, or lasting devices. In case the further inflow is shut off, the valve-devices may be given proper position to maintain the pressure while such adjustments are being made, following which the inflow-port or ports may be opened again to admit additional pressure to effect with any desired degree of force the further relative movement required for the lasting. It will be perceived that it is possible to produce a dwell with any desired degree of pressure, or to produce an increase of pressure, or to pro-

duce a relaxation of the pressure when back-
ing-off or relaxation is deemed to be desira-
ble or necessary. In practice, in addition to
forcing the last and shoe down within the
nest or circle of the lasting devices, as men-
tioned, for the purpose of effecting the pre-
liminary wiping operation, the depressor
and hold-down is caused to hold the last and
shoe down while the final operations are be-
ing performed.

In case the convenient control is desired
but without elasticity, water or oil may be
utilized as the pressure-transmitting medi-
um, instead of air, steam or gas.

The invention provides means responding
readily to the operator's control, and by
which relative movement, and either the ap-
proach or the entry or the lasting action,
may be caused to take place at any desired
speed and with any desired force. The said
means permits the speed and force to be
varied at the will of the operator from mo-
ment to moment in such manner and to such
extent as in the judgment of the operator
may be advisable or required, enabling him
thereby to cause the approach to take place
at first at a higher rate of speed and then
later proceed more slowly. The employment
of elastic fluid-pressure enables the relative
approach to be caused to take place with
comparative quickness, but with yielding
force so as to obviate danger of injuring the
material of the upper through the applica-
tion of too great a strain or too much pres-
sure. Resistance to the relative movement,
operating with a tendency to retard or pre-
vent such movement, is accompanied by an
accumulated pressure, the relative movement
proceeding at a decreased rate of speed but
with increasing force as required in drawing
the upper into place upon the last and caus-
ing it to conform to the same, without loss
of the elastic action, however. The pressure
is governed at will to provide for continuing
the action upon the upper, or for suspending
it and holding the parts and the upper with-
out change or relaxation of the pressure
while adjustments or hand-operations are
effected, and subsequently continuing the ac-
tion again, all as may be required in connec-
tion with the work of causing the upper to
assume the desired position upon the last

and conform thereto, and in adapting the
action as may be found necessary to the char-
acter and strength or delicacy of the upper. 55

What is claimed as the invention is:—

1. In a lasting-machine, the combination
with lasting devices adapted by or through
entry of the last with shoe thereon and rela-
tive movement between the last and the said 60
devices to draw the upper of the shoe into
place around the last, of a depressor, and
fluid-pressure means for occasioning at the
will of the operator the relative approach,
entry, and resulting lasting operations un- 65
der continuous control by the operator of the
relative movement, its speed, its direction,
and the intensity of the applied pressure.

2. In a lasting-machine, the combination
with lasting devices adapted by or through
entry of the last with shoe thereon and rela-
tive movement between the last and the said 70
devices to draw the upper of the shoe into
place around the last, of a depressor and
hold-down, toggle-lever operating devices 75
therefor, and fluid-pressure means for actu-
ating said toggle-lever operating devices at
the will of the operator to operate thereby
the depressor and hold-down to produce the
approach of the last with shoe thereon and 80
entry of the same within the lasting devices
and thereby effect a lasting action under con-
tinuous control by the operator of the rela-
tive movement, its speed, its direction, and
the intensity of the applied pressure. 85

3. In a lasting-machine, the combination
with lasting devices adapted by or through
entry of the last with shoe thereon and rela-
tive movement between the last and the said 90
devices to draw the upper of the shoe into
place around the last, of a depressor, and
elastic-fluid-pressure means for occasioning
at the will of the operator the relative ap-
proach, entry, and resulting lasting opera- 95
tions, under continuous control by the oper-
ator of the relative movement, its speed, its
direction, and the intensity of the applied
pressure.

In testimony whereof I affix my signature
in presence of two witnesses.

FRANK W. MERRICK.
